UNITED STATES PATENT OFFICE

2,462,421

CROSSFLOW HEAT EXCHANGER

Paul A. Pitt, San Diego, Calif., assignor to Solar Aircraft Company, San Diego, Calif., a corporation of California

Application October 26, 1944, Serial No. 560,369

5 Claims. (Cl. 257—245)

1

This invention relates to heat exchangers of the cross-flow type, in which two fluids between which heat transfer is to take place flow in directions substantially at right angles to each other. More particularly, it relates to that type of cross-flow heat exchanger in which a series of generally flat thin metal sheets are so secured together at their edges as to define the two sets of passages.

The invention is particularly useful on aircraft for heating air by the exhaust gas from the engine where the temperature differential between the exhaust gas and the air to be heated is frequently very great. Thus the temperature of the air at high altitudes is frequently 60° F. or more below zero whereas the exhaust gas may be 1800° F. or more above zero. As a result, different parts of the heat exchanger, only a few inches apart, may acquire temperatures differing by as much as 1200° F. Because of the resultant different expansions and contractions of relatively closely spaced parts of the heat exchange structure, severe stresses are developed that eventually result in the break-down of a structure that would be adequate when subject to less severe temperature differentials.

A general object of the present invention is to increase the life of heat exchangers of the type mentioned.

Another object is to reduce the temperature differentials between inside and outside portions of a heat exchanger of the type described and thereby reduce differential expansions between the parts.

Another object is to prevent vibration of the plates or sheets of a heat exchanger.

Still another object is to provide a structure that permits the sheets to bend in response to differential expansion caused by unavoidable temperature differentials.

Ordinarily there is a marked difference in the temperatures of the outside sheets of a heat exchanger and the interior sheets because the interior sheets are exposed only to the cooling effect of the cooling fluid that is flowing through the heat exchanger whereas the outside plates are exposed not only to the cooling medium flowing therethrough but also lose heat by radiation. In accordance with the present invention, I reduce the differential temperature between the inner and outer sheets of the exchanger by throttling the flow of cooling fluid through the outer passages so that less heat is absorbed from the outer plates by the cooling fluid, to com-

2

pensate for the heat lost from those plates by radiation.

I reduce vibration of the plates, in accordance with the present invention, by providing corrugations or beads extending in both directions across the plates and either in contact with or welded to the corrugations of the adjoining plates so as to reduce the free areas of the plates to stiffen them and reduce opportunity for drumming. I also so form the corrugations that they facilitate gradual bending of the sheets in response to differential expansion of different portions of the sheets so as to reduce the overall stresses due to unequal expansion and which ordinarily produce failure of the structure within a relatively short time.

Various more specific objects and features of the invention will become apparent from the following detailed description of a specific embodiment of the invention, as illustrated in the drawing:

In the drawing:

Fig. 1 is a side elevation view of the core of a heat exchanger in accordance with the invention, portions of the structure being broken away;

Fig. 2 is a cross section of the core shown in Fig. 1, with the outer casing shown in section and a portion of the core broken away to show how it appears in a different plane;

Fig. 3 is a perspective view, with parts broken away, showing the corner construction of the heat exchanger; and

Fig. 4 is a plan view of one of the sheet units that make up the core.

Referring to Fig. 1, there is disclosed a cross-flow heat exchanger having a core of special construction in accordance with the invention, which core is adapted to be contained in a casting. The particular exchanger illustrated is of approximately square cross section and is of greater length than width. It is intended for use for heating air from the exhaust gas of an airplane engine and, as usually employed, the exhaust gas is passed longitudinally through the exchanger and the air is passed through it transversely.

The core of the exchanger consists of a plurality of similar units 13, each of which constitutes a conduit extending longitudinally of the exchanger and, in this instance, conveying hot exhaust gas. Each unit 13 consists of two formed sheets 15 and 16 in spaced relation over the major portion of their areas but brought together and welded at their lateral edges 14, and having opposite corrugations 17 spaced inter-

mediate the edges 14, the corrugations on the two sheets 15 and 16 being also welded together so that three distinct longitudinal passages 18, 18 and 18 are formed by each unit 13.

The lateral edges 14 of each unit 13 are flattened at the corners, as shown in Fig. 3, to form vertical corner edges 22 on each unit.

The lower sheet 15 of each intermediate unit 13 is connected to the upper sheet 16 of the next unit therebelow at each end by a clip 20, as indicated in Figs. 1 and 3, and each intermediate cross-flow passage 21 is defined by the sheet 15 of one unit 13 and the sheet 16 of the next adjacent unit 13.

The joinder of the horizontal end edges of the units by the clips 20, as described, maintains the corner edges 22 of the various units in alignment and they are welded together to maintain a separation of the cross-flow passages 21 from the longitudinal passages 18.

To conduct fluid to and from the longitudinal passages 18, transition members 24 and 25 are provided at the opposite ends of the core. The transition member 24 is rectangular in cross-section at its inner end and fits in and is welded to a rectangular collar 241 which in turn is welded to the left end edges of the top wall 16 of the top unit 13 and of the bottom wall 15 of the bottom unit 13. The other two edges of the collar 241 are welded to the vertical edges of the core, which are constituted by the aligned corner edges 22 of the various units 13. The outer end of the square collar 241 is turned out to form a flange 242. The transition member 25 is joined to a square collar 251 having an outwardly extending flange 252, and the collar 251 is joined to the right end of the core of the exchanger in the same manner that the collar 241 is joined to the left end thereof.

Upper and lower casing walls 26 and 27, respectively, are provided above and below the top and bottom units 13, to provide a pair of outer transverse passages 21a for conveying fluid past the outer sides of the upper and lower units 13. These casing walls 26 and 27 are secured at their ends to the transition members 24 and 25 and are provided with groove-defining attachment flanges 28 for receiving conduits which convey fluid to and from the cross-flow passages. As previously stated, ordinarily the fluid flowing through the cross passages 21 and 21a will be the cooler fluid, such as air, whereas the fluid flowing through the longitudinal passages 18 would be exhaust gas at a high temperature.

Although the outer cross-flow passages 21a are highly desirable for the reason that they provide additional capacity for the exchanger, I have found that as a result of the heat loss to the air flowing through passages 21a, in addition to the heat loss by radiation to and through the outer casing wall 26, which is exposed to the surrounding air, the outer sheet 16 of the top unit 13 may run at a much lower temperature than the inner sheet 15. Likewise the lower sheet 16 of the bottom unit 13 may run at a lower temperature than the top sheet of that unit. These differences in temperature produce differential expansions in the two walls of the outer units 13 which materially shorten their lives. I have found that this inequality in temperature may be largely corrected by providing baffles 29 at one end of each passage 21a. These baffles 29 are preferably provided at the inlet end although this is not essential. The baffles are so proportioned by test as to produce substantially equal

temperatures in the two sheets 15 and 16 forming the outer units 13.

As already described, the sheets 15 and 16 of each unit 13 are welded together at their edges 14 and at the beads or corrugations 17 so that the lateral dimensions of the sheets between points of joinder are relatively small, thereby reducing the opportunity for free vibration of the plates.

To further stiffen and support the plates, they are provided with externally projecting transverse corrugations 30, and the corrugation 30 of each plate 15 of one unit 13 contacts the corrugation 30 of the adjacent plate 16 in the next adjacent unit 13. This construction is most clearly shown in Fig. 1. It has the advantage of providing mutual support between the plates at relatively closely spaced points longitudinally so as to reduce the unsupported length of any section of each sheet.

It is found in practice that substantial temperature differences may obtain between the edge portions 14 and the corrugated portions 17 of each unit 13, relative to the unsupported areas intermediate the joined portions 14 and 17. These differences in temperature result in unequal expansion, which in older designs have produced severe stresses at the ends of the sheets. In accordance with the present invention, I reduce these stresses by making the plates 15 and 16 of undulate form, as indicated at 15a and 16a in Fig. 1, intermediate the ends of the core and intermediate successive cross ribs or corrugations 30. This undulate shape permits unequal expansion of the joined portions 14 and 17 relative to the remaining portions by facilitating bending within the undulate portion. It will be observed that both sheets 15 and 16 of each unit 13, and of the different units 13, are all curved similarly, so that the passages are of substantially the same cross sectional area at all points. An exception is that the cross-flow passages 21 are larger adjacent the corrugations 17. However, these enlarged portions are beneficial to promote turbulence of the air flowing through the passages 21.

The heat exchanger described is preferably constructed by first forming the units 13 individually by seam-welding the edges 14, and the corrugations 17 together. Thereafter, the elements 13 are stacked together and flame or arc welded together at the ends 20. Following assembly of the core, along the vertical corner edges 22, along the end edges of the top wall 16 of the top unit 13, and along the end edges of the bottom wall 15 of the bottom unit 13, the transition members 24 and 25 may be welded to the ends of the core, after which the upper and lower casing walls 26 and 27 can be welded or joined in other manner to the transition members 24 and 25.

Although for the purpose of explaining the invention a particular embodiment thereof has been described in detail, various departures from the exact construction shown can be made without departing from the invention which is to be limited only to the extent set forth in the appended claims.

I claim:

1. In a heat exchanger of the cross-flow type having a first set of generally flat parallel passages extending in one direction for conducting a first fluid that is above ambient temperature and having a second set of generally flat parallel passages interleaved with the first set and extending in a direction substantially at right angles to

said one direction for conducting a second, cooler, fluid, the construction comprising: a plurality of generally flat sheets in generally parallel spaced relation with successive pairs of sheets joined directly together along one pair of opposite edges and defining flat conduit units constituting the sole essential structure forming said first set of passages, and the adjacent sheets of each adjacent pair of said conduit units being joined directly together along their other pairs of opposite edges for defining all of the interior passages of said second set of passages; auxiliary casing walls parallel and in outwardly spaced relation to the outermost of said sheets for defining therewith the outermost passages of said second set of passages; and baffle means extending across said outermost passages at one end thereof for restricting the velocity of flow of said second cooler fluid through said outermost passages more than through the interior passages of said second set to reduce the temperature differential of said outer sheets relative to the remaining sheets.

2. In a heat exchanger of the cross-flow type having a first set of generally flat parallel passages extending in one direction for conducting a first fluid that is above ambient temperature and having a second set of generally flat parallel passages inter-leaved with the first set and extending in a direction substantially at right angles to said one direction for conducting a second, cooler, fluid, the construction comprising: a plurality of generally flat sheets in generally parallel spaced relation with successive pairs of sheets joined directly together along one pair of opposite edges and defining flat conduit units constituting the sole essential structure forming said first set of passages, and the adjacent sheets of each adjacent pair of said conduit units being joined directly together along their other pairs of opposite edges for defining all of the interior passages of said second set of passages, said sheets having straight corrugations extending longitudinally of and projecting into said first passages and the corrugations the full length of each pair of sheets that define one of said first passages merging and being welded together, whereby said sheets are reinforced.

3. In a heat exchanger of the cross-flow type having a first set of generally flat parallel passages extending in one direction for conducting a first fluid that is above ambient temperature and having a second set of generally flat parallel passages inter-leaved with the first set and extending in a direction substantially at right angles to said one direction for conducting a second, cooler, fluid, the construction comprising: a plurality of generally flat sheets in generally parallel spaced relation with successive pairs of sheets joined directly together along one pair of opposite edges and defining flat conduit units constituting the sole essential structure forming said first set of passages, and the adjacent sheets of

each adjacent pair of said conduit units being joined directly together along their other pairs of opposite edges for defining all of the interior passages of said second set of passages, each pair of adjacent sheets that defines a passage of said first set being longitudinally straight at their joined edges and being longitudinally undulate intermediate their joined edges, whereby the intermediate portions can yield to compensate for relative expansion and contraction of the edge portions with respect to the intermediate portions.

4. A heat exchanger as defined in claim 3, in which the two sheets of each pair defining one of said second passages have juxtaposed corrugations extending longitudinally of and projecting into the second passages into contact with each other.

5. In a heat exchanger of the cross-flow type having a first set of generally flat parallel passages extending in one direction for conducting a first fluid that is above ambient temperature and having a second set of generally flat parallel passages inter-leaved with the first set and extending in a direction substantially at right angles to said one direction for conducting a second, cooler, fluid, the construction comprising: a plurality of generally flat sheets in generally parallel spaced relation so joined together at their edges that they constitute the sole essential structure defining said first set of passages and all the interior passages of said second set, each pair of adjacent sheets that defines a passage of said first set being longitudinally straight at their joined edges and having straight longitudinal corrugations welded together and spaced from each other and from said joined edges, the two sheets of each pair defining one of said second passages having juxtaposed straight corrugations extending longitudinally of and projecting into the second passage into contact with each other, said sheets being longitudinally undulate intermediate their joined edges and said joined corrugations and intermediate the corrugations projecting into said second passages, whereby the unsupported portions of said sheets can yield to compensate for relative expansion and contraction of said different portions of the sheets.
